US00D869400S

(12) **United States Design Patent** (10) **Patent No.:** **US D869,400 S**
Wu (45) **Date of Patent:** **** Dec. 10, 2019**

(54) **REINFORCED ELECTRICAL CONTACT**

(71) Applicants: **DINKLE ENTERPRISE CO., LTD.**,
 New Taipei (TW); **DINKLE**
ELECTRIC MACHINERY (CHINA)
CO., LTD., Kunshan, Jiangsu (CN)

(72) Inventor: **Shang-Tsai Wu**, New Taipei (TW)

(73) Assignees: **DINKLE ENTERPRISE CO., LTD.**,
 New Taipei (TW); **DINKLE**
ELECTRIC MACHINERY (CHINA)
CO., LTD., Kunshan, Jiangsu (CN)

(**) Term: **15 Years**

(21) Appl. No.: **29/662,480**

(22) Filed: **Sep. 6, 2018**

(51) LOC (12) Cl. **13-03**

(52) U.S. Cl.

USPC **D13/154**; D13/133

(57) **CLAIM**

The ornamental design for a reinforced electrical contact, as
 shown and described.

DESCRIPTION

FIG. 1 is a perspective view of a reinforced electrical contact
 showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is second perspective view showing the reinforced
 electrical contact.

The Dash-Dash broken line portion of the figure drawings is
 included to show portions of the article that form no part of
 the claimed design. The Dash-Dot broken line portion of the
 figure drawings is included to show claim boundaries that
 form no part of the claimed design.

1 Claim, 8 Drawing Sheets
